UNITED STATES PATENT OFFICE

GEORGE H. GILMAN, OF CLAREMONT, NEW HAMPSHIRE, ASSIGNOR TO SULLIVAN MACHINERY COMPANY, A CORPORATION OF MASSACHUSETTS

TOOL

Application filed June 23, 1919. Serial No. 306,014.

This invention relates to tools, and more especially to that type of tool used for drilling holes in mines or quarries and usually operated by a suitable pressure fluid, such as 5 compressed air.

One object of the present invention is to provide an improved drilling tool having improved means for washing the cuttings from the working surface and for giving direction 10 to the washed cuttings so that the latter do not interfere with the operation of the tool. Another object of the present invention is to provide improved means for lubricating the tool when it is started, and thereby render it 15 unnecessary for an operator to detach the hose and inject a quantity of oil therein before starting, as is commonly done. Still another object of the present invention is to provide improved controlling means for controlling 20 the motor, the lubricating means, and the feeding means, so that the flow of compressed air, lubricant, and water to the various parts of the motor must necessarily occur in a predetermined sequence to thereby bring the operation of the motor within the control of 25 even the most unskilled operator. The foregoing and other objects of the invention will best be understood from the following description of two forms or embodiments there- 30 of illustrated in the accompanying drawings.

In these drawings,—

Fig. 1 is a top plan view of the motor with the pneumatic feeding means thereof shown partly in section.

Fig. 2 is a longitudinal sectional view thereof through the percussive motor taken substantially on the line 2—2 of Fig. 1.

Fig. 3 is a transverse sectional view through the controlling means, taken substantially on the line 3—3 of Fig. 2.

Fig. 4 is a transverse sectional view through a part of the rotating mechanism, taken substantially on the line 4—4 of Fig. 2.

Fig. 5 is another transverse sectional view 45 through the rotating mechanism, taken substantially on the line 5—5 of Fig. 2.

Figs. 6, 8, and 9 are partial longitudinal sectional views through the controlling mechanism taken substantially on the lines 6—6, 50 8—8, and 9—9, respectively, of Fig. 1, show-

ing the controlling valve in different controlling positions.

Fig. 7 is another longitudinal sectional view through the controlling mechanism of the motor, taken substantially on the line 2—2 55 of Fig. 1.

Fig. 10 is a partial longitudinal section taken on line 10—10 of Fig. 3.

Fig. 11 is a transverse sectional view through a part of the feed controlling means, 60 taken on line 11—11 of Fig. 1.

Fig. 12 is a longitudinal sectional view of a modified form of pneumatic tool.

Fig. 13 is an enlarged detail of the lubricating valve. 65

In the illustrative construction shown in Figs. 1 to 11, inclusive, I have shown a drilling apparatus having a pneumatic tool 1 and a controlling valve 2, with a controller handle 3 therefor, a chuck 4 adapted to receive a drill steel 5, and to rotate the same during the drilling operation. The pneumatic tool 1 is preferably fed forward toward the work by a feeding means, herein shown as operated by pressure fluid, the same having a feed cylinder 6, a feed piston 7 therein, with its piston rod 8, the latter having longitudinal openings 9 therethrough, through which fluid is admitted, preferably by the controlling valve 2, to properly feed the tool toward its work. Herein I have also shown a braking means 10 applied to the forward end of the feed cylinder and operable in a well known manner to brake a reciprocatory movement of the piston rod 8 and thereby vary the movement of the tool. As shown, my preferred form of braking means is controlled by a handle 12 which actuates a worm 13, the worm in turn operating a worm gear 14, and the gear 14 actuates one end of a coiled spring 70 75 80

15 which surrounds and may be made to frictionally engage the feed piston rod 16, it being understood that the other end of the spring is attached to the feed cylinder 6 or means cooperating therewith. 85 90 95

The piston 18 of the tool is preferably reciprocated by compressed air admitted through an inlet 19, ports 20, and a recess 21 in the piston to bypasses 22, which in turn open into the opposite ends of the cylinder 100

through suitable ports 23, 24, the movement of the piston controlling the flow of air to the bypasses. Cooperating with the pneumatic tool, I also provide a hollow handle or arm 5 by means of which the operator may hold the tool against rotation, and which also serves in a well known manner as an oil reservoir from which lubricant may be taken to lubricate the different parts of the motor. 10 As is clearly shown in Fig. 3, the hollow interior 26 of this handle communicates through suitable ports 27 with a recess 28, preferably spooled out of the inner end of the handle 25, this recess 28 in turn communicating with 15 a lubricant controlling valve 29 (see Figs. 10 and 13) and also with a passageway 30 in the rear cylinder head 31. This valve 29 is preferably placed in a dowel pin 32 which holds the cylinder 33 and the cylinder head 20 31 against relative rotation as shown in Fig. 10. As the piston 18 is reciprocated in the cylinder 33, varying air pressures in a passageway 34 in the rear cylinder head, which 25 conducts pressure fluid from the hollow center of the valve 2 of the cylinder 33, intermittently raises the valve head 35 of the small oil controlling valve 29 against the action of a spring 36, and permits a small quantity of 30 pressure fluid to enter the oil reservoir by way of a port 34^a, annular groove 32^a, and a transverse passage 32^b in turn communicating with a longitudinal passage 35^a controlled by the valve head 35 of the valve 29. Fluid 35 pressure flows past the valve 29 and to the reservoir 26 by way of a transverse passage 36^a communicating with the bore for the valve 29 and an annular groove 36^b from which a passage 31^a leads to the reservoir 26, it being understood that the valve 29 is not a 40 tight fit and hence allows sufficient leakage of pressure fluid thereby. Fluid pressure can flow to the reservoir or a small quantity of oil may pass from the reservoir into the cylinder. Due to the fluctuating pressure 45 within the chamber 34 the pressure within the reservoir will at times be greater than in said reservoir and accordingly lubricant will be forced past the valve and into the chamber 34. In actual practice an ordinary running fit for the valve is sufficient to permit oil to pass from the reservoir to the chamber 34 or air pressure to pass from the chamber to the reservoir. When the machine is not 50 in operation, the small coiled spring 36 holds the valve 35 against its seat and prevents leakage of oil into the cylinder.

The oil duct 30 preferably communicates with a short groove 37 formed in the outer surface of the bushing 38 of the conical valve 60 member 39 and conducts oil from the reservoir to a longitudinal groove 40, which in turn, in one position of the valve deposits some of this oil in a small external oil reservoir, recess, or pocket 41, through suitable 65 holes 42 cut through the valve bushing. In

another position of this valve, lubricant is also transferred to an oil pocket or reservoir 43, herein shown as formed in the inner wall of the valve bushing 38 and in communication with the interior of the valve 39, to which air or other pressure fluid is supplied through a suitable hose 44 and coupling 45. When the valve is in the neutral position shown in Fig. 6, oil will be transferred into the longitudinal groove 40 and pocket 41, and as the valve is turned the oil in the groove will be deposited in the pocket 43, the flow of air from the conical valve 2 to the pneumatic cylinder 33 to actuate the piston 18 carrying lubricant from the pocket 43 and depositing this initial charge in the cylinder before sufficient pressure has been created in the reservoir or handle 25 to cause lubricant to flow past the lubricant controlling valve 29 into the cylinder. When the valve member 39 is 85 turned to the position illustrated in Fig. 7, a small radial opening 46 in the valve member 39 communicates with one of the openings 42 and forces the oil from the pocket 41 through the other opening 42, a groove 47 formed preferably in the wall of the conical valve member 39, and through a longitudinal duct 48, into the forward end of the cylinder and preferably into the ratchet mechanism 49 which rotates the chuck and the steel. 95

This rotating mechanism may be of a variety of forms, but herein it is illustrated as a ratchet ring 50, preferably formed of substantially the same diameter as the cylinder 33, and a ratchet wheel 51 carrying suitable spring pressed pawls 52 which cooperate with teeth on the inner surface of the ratchet ring 50. This ratchet wheel is also provided with rifled feathers 53 which co-operate with rifled grooves 54 on a hammer bar 55 to rotate the chuck, this rotation being transmitted from the rifle bar to the chuck by longitudinal grooves 56, herein shown as formed on the rifle bar, and cooperating longitudinal feathers 57 formed on the inner surface of the chuck. 100

The oiling mechanism above described will inject a sufficient quantity of oil into the rotating mechanism to lubricate this during the starting period, the pocket or recess 41 being made as large or small as desired, it being preferably made quite small, for in practice it has been found that when spotting a hole the operator will turn the valve off and on several times, and since at each operation of the handle from a neutral position, a charge of oil is forced into the rotating mechanism, a large pocket is not required. While, if desired, means may be provided for lubricating the chuck during operation from the oil reservoir 25, I preferably provide a second oil reservoir 58, preferably formed on a cylinder extension 59 which serves also as a retainer for the rotating chuck, the lubricant being fed from the reservoir to the inside of 110

115

120

125

130

the retainer through a small duct 60 and therefrom to the rotating mechanism. In practice it has been found that the different parts of the chuck, which are herein shown as threaded together, may be fitted very tightly into the sleeve 59, for the jar of the machine during its operation will feed the oil downwardly through the duct 60 to the bearing surfaces between the chuck and the sleeve 59 and into the rotating mechanism in sufficient quantity to adequately lubricate the bearing surfaces and the rotating mechanism. The initial supply of lubricant is preferably injected into the rotating mechanism, as shown in Fig. 7, just previous to the forward movement of the pneumatic tool toward the work, which movement, as illustrated in Fig. 8, is brought about by the permitting of a flow of pressure fluid from the conical valve member 39 of the valve 2, preferably through a small port 61 which is formed in the valve in advance of the main port 62 and the recess 63 communicating therewith, so that when even an unskilled operator turns the valve to feed the tool toward the work but a small quantity of pressure fluid will be permitted to flow to the tool feeding means to feed the tool slowly and thereby permit accurate spotting of the hole. After the end of the drill steel has been accurately placed at the desired point, the valve may be turned further and the full benefit of the pneumatic feeding means be availed of, by taking advantage of the flow of pressure fluid through the relatively large port 62.

As the valve is thus turned to use the additional pressure in the feeding means, a small port 64 (Fig. 10) permits the flow of pressure fluid to the pneumatic tool to start the latter slowly and carry a small quantity of oil from the pocket 43 into the motor. The use of this small port 64 which is preferably formed in the valve in advance of the main port 65 for controlling the flow to the pneumatic cylinder 33, is a feature of the present invention, for it limits the operation of the piston on the steel during the spotting of the hole and tends to keep the steel from jumping about on the face of the work, especially when the hole is to be spotted on an inclined surface.

Before the valve member 39 is rotated far enough to permit a flow of pressure fluid to the pneumatic tool, and preferably simultaneously with the injection of oil to the rotating mechanism, a small port 66 formed on the valve member 39 in advance of the large port 67 and recess 68 (Fig. 7) communicates with a port 69 formed in the valve bushing, and with a duct 70, to carry pressure fluid therethrough and through a laterally apertured spacing member 71 to the interior of a tube 72, which is preferably brazed to said spacing member and which extends axially through the piston into the bore 73 of the

tappet 74, herein shown as placed within the chuck. The tube 72 at its rear end is preferably held fixedly in the rear cylinder head by the spacing member and also by means of a compressible packing 75, so that the forward end of this tube does not extend through the tappet but preferably terminates a small distance short of the front end thereof. This initial flow of air through this tube clears the steel of cuttings and other foreign material. As the valve member 39 is turned further through manipulation of the handle 3, water is conducted from a water hose 76 and suitable couplings 77 and a groove 78, shown herein as formed on the outer surface of the valve member 39 (Fig. 9), through a duct 79 and a recess 80 to the interior of an axially apertured gland plug 81, and therefrom through an inner tube 82 also extending axially through the piston and herein shown as placed within the air tube 72. The forward end of this tube preferably extends within the bore 83 of the hollow drill steel to conduct the water to the interior of the steel at a point in front of the terminal of the tube 72. When both water and air are flowing to the hollow drill steel to wash the cuttings away from the working end thereof, the air admitted through the tube 72 forms a seal around the front end of the water tube 82, between the latter and the inner wall of the steel, and also around the bottom of the drill shank, to prevent cuttings which are washed down the drill shank to the interior of the chuck from flowing through the tappet and into the rotating mechanism and the cylinder 33. The tappet 74 delivers the blow from the piston rod extension or rifle bar 55 to the steel and partially closes the front end of the pneumatic motor, and, cooperating with the air seal above described, completely closes the front end of the pneumatic tool to the downward flow of the cuttings. The latter are directed from the inner bore of the chuck to substantially radial openings 84 which communicate with passageways 84' which direct the cuttings substantially parallel to the axis of the motor and tend to prevent their being thrown outward onto the operator as the chuck is rotated during the drilling operation. The tubes 72 and 82 are held fixedly in the rear cylinder head 31 by the gland plug 81 and in spaced relation by the spacing member 71, each of these members being in communication with separate ducts to supply separate fluids to each of these tubes, and the rear end of the gland and the recess 80 being closed by a cover 85 which is detachably secured to the rear side of the head. These tubes or any of the ducts communicating therewith may be easily inspected after removal of the pneumatic feeding means, by merely removing the cover 85 and the gland plug 81 through the rear side of the cylinder head.

In the operation of the tool, it is understood that when the machine is set up for drilling purposes, the valve handle 3 will be set in the position shown in Fig. 6, an arrow being shown in this and succeeding figures on one prong of the handle to show the relative positions of the handle as the latter is rotated to secure the desired control of the apparatus. In this position, (Fig. 6) which I preferably term the neutral position, the oil passage 40 is in communication with the pocket 41, and the oil reservoir 25, and the pocket is filled with lubricant. When the handle is rotated to the position shown in Fig. 7, an initial supply of oil is injected into the rotating mechanism and a small quantity of pressure fluid is admitted through the tube 72 to clear the hollow bore of the steel. As the valve is turned further to the position shown in Fig. 8, air is admitted through the small port 61 to the feeding means to feed the cylinder 33 forward slowly toward the work, the air flowing through the tube 72 still continuing. The groove 68 is so formed that during the succeeding operation of the controlling handle pressure fluid may be continuously admitted through the tube 72 to clear away the cuttings and to carry the water to the working surface and prevent the cuttings from entering the tappet rotating mechanism or the cylinder 33. When the valve is in the position shown in Fig. 9, water is admitted to the inner tube 82 and is carried forward by the air to the cutting end of the steel, the groove 63 now being in communication with the feed cylinder to force the bit hard against the material to be cut. When the valve is in the final or open position illustrated in Fig. 10, the pneumatic motor is operating at its full power to drive the bit forward into the rock, oil is being admitted through the valve 29 from the reservoir 25 to lubricate the motor, air and water are being admitted through the respective tubes to the inner bore of the drill steel, and the ratchet mechanism is being lubricated from the reservoir 58.

If desired, the preferred form of my invention as illustrated in Figs. 1 to 11, inclusive, may be modified by omitting the rotating mechanism, as illustrated in Fig. 12, the tappet 86 being operated on directly by the piston to drive the steel forward, the air tube 87 terminating preferably within this tappet in the same manner as described above and illustrated in Fig. 2. Also, if desired, the motor may be used as a "dry stoper" by doing away with the water hose 76 and its connections 77, or by using a different valve member 88 in place of the conical valve member 39, which does not have the ports and grooves necessary for placing the water hose 76 in communication with the inner axial water tube 82, it being understood that when the apparatus is used as a "dry stoper" neither of these water tubes is

required, and that both may be accordingly dispensed with.

It will thus be seen that I have provided an improved drilling tool in which all the parts are adequately lubricated and in which an initial supply of lubricant is provided for all the working parts, so that if the apparatus is taken from stock for use in a mine or quarry it is not necessary to disassemble and pack the different parts in grease preparatory to the starting. It will also be noted that in the lubricating system for the cylinder, the varying pressure in the cylinder is utilized for building up a pressure in the receiver 25, which pressure positively forces the oil from this reservoir to the controlling valve to lubricate the latter, and to the groove 40 and pocket 41, insuring adequate supply of oil to these recesses and also from the reservoir through the intermittently acting valve 29 to the motor. It will further be noted that by my improved construction I have provided means for conducting cleansing fluids to the hollow bore of the steel in such a manner that the liquid used for washing away the cuttings is carried through the steel to the working end thereof, and that the washed cuttings cannot flow downwardly into the chuck and therefrom into the tool, these cuttings rather being blown downwardly through passageways 84 by the blast of air which will pass around the lower end of the drill steel as the latter rebounds from the tappet after each blow. Another feature of the invention is the improved controlling means whereby an initial flow to the feed cylinder and an initial flow to the pneumatic tool are provided so that the tool is fed slowly toward the work and is started slowly to facilitate the spotting of a hole. The improved controlling valve also provides means for preventing the flows to the feeding means, to the motor, to the lubricating means, and to the hollow drill steel in an improper sequence so that even the most unskilled operator will not cause damage to the tool or cause delay in starting a hole by an improper manipulation of the controlling means, or that the operator will not carelessly blow cuttings into his face or the faces of other operators, causing injury to himself and others and causing delay in the working of the cutting or tunnel.

While I have in this application specifically described two embodiments which my invention may assume in practice, it will be understood that these forms are used for illustrative purposes, and that the invention may be modified and embodied in various other forms without departing from its spirit or the scope of the appended claims.

What I claim as new and desire to secure by Letters Patent is:

1. In a fluid actuated motor having a plurality of parts including a cylinder and a

5 rear head member, means for holding said head member and cylinder against relative movement including a dowel pin, a lubricant reservoir and passage means for placing said reservoir in communication with said cylinder including passage means through said dowel pin, and an automatic valve in said dowel pin for controlling flow of lubricant from said reservoir to the motor.

10 2. In a pressure fluid motor, a cylinder, a cylinder head, means forming a lubricant reservoir attached to said head, a pressure chamber formed in said head, a passage connecting said reservoir with said pressure chamber, a discharge passage connecting said reservoir with said cylinder, and means responsive to the pressure conditions in said motor cylinder for controlling the flow of lubricant from said reservoir thereto.

15 3. In a pressure fluid motor, a cylinder, a cylinder head, a lubricant reservoir, a valve carried by said head, a pressure chamber in said head communicating with said cylinder, said valve controlling the flow of fluid to said pressure chamber, a passage connecting said pressure chamber with said reservoir, passage means controlled by said valve for connecting said reservoir with said motor cylinder, a discharge connecting said reservoir with said motor cylinder, and means responsive to pressure conditions in said motor cylinder for controlling the flow of lubricant through said latter discharge means.

20 4. In a motor, a cylinder, a piston therein, pneumatic cylinder feeding means, a chuck, a chuck rotating mechanism, a plurality of fluid conducting means for supplying a cleansing liquid and a cleansing fluid to a hollow tool receivable in said chuck, a lubricant reservoir, and a single controlling means for admitting an initial flow of oil to the rotating mechanism, a flow of fluid to one of said conducting means, and a flow of pressure fluid to said cylinder.

25 5. In a motor, a cylinder, a piston therein, pneumatic cylinder feeding means, a chuck, a chuck rotating mechanism, a plurality of fluid conducting means for supplying a cleansing liquid and a cleansing fluid to a hollow tool receivable in said chuck, a lubricant reservoir, and a single controlling means for admitting an initial flow of oil to the rotating mechanism, a flow of fluid to one of said conducting means, a flow of pressure fluid to said feeding means, and a flow of pressure fluid to said cylinder, the flow of fluid to said cylinder being permitted after said other fluid flows as the controlling means is moved from neutral position.

30 6. In a motor, a cylinder, a piston therein, pneumatic cylinder feeding means, a chuck, a chuck rotating mechanism, a plurality of fluid conducting members for supplying a cleansing liquid and a cleansing fluid to a hollow tool receivable in said chuck, a lubri-

cant reservoir, and a single controlling means for admitting an initial flow of oil to the rotating mechanism, a flow of fluid to one of said conducting means, an initial, predetermined flow of pressure fluid to said feeding means, and a flow of pressure fluid to said cylinder, the flow of fluid to said cylinder being admitted last as said controlling means is moved from neutral position.

70 7. In a tool, a pressure fluid motor comprising a cylinder and a piston therein, a tool chuck, a chuck rotating mechanism, a fluid conducting means for conducting a cleansing fluid to a hollow tool receivable in said chuck, a lubricant reservoir, and a single valve for effecting an initial flow of lubricant to said motor cylinder and to said rotating mechanism, a flow of cleansing fluid to said cleansing means, and a flow of pressure fluid to said motor cylinder, said events occurring in a predetermined sequence.

75 8. In a tool, a pressure fluid motor comprising a cylinder and a piston therein, a tool chuck, a chuck rotating mechanism, a plurality of fluid conducting means for conducting a cleansing liquid and a cleansing fluid to a hollow tool receivable in said chuck, a lubricant reservoir, and a single valve for effecting an initial flow of lubricant to said motor cylinder and to said rotating mechanism, and a flow of cleansing fluid to one of said cleansing fluid conducting means, and thereafter a flow of pressure fluid to said motor cylinder, and a flow of liquid to said other cleansing fluid conducting means, said events occurring in a predetermined sequence.

80 9. In a tool, a pressure fluid motor comprising a cylinder and a piston therein, a tool chuck, a chuck rotating mechanism, a plurality of fluid conducting means for conducting a cleansing fluid to a hollow tool receivable in said chuck, a lubricant reservoir, and a single valve for effecting an initial flow of lubricant to said motor cylinder, and to said rotating mechanism, and a flow of cleansing fluid to said cleansing means, and for thereafter admitting a flow of pressure fluid to said motor cylinder, said events occurring in a predetermined sequence.

85 10. In a tool, a pressure fluid motor comprising a cylinder and a piston therein, a tool chuck, a chuck rotating mechanism, a fluid actuated feeding mechanism, a fluid conducting means for conducting a cleansing fluid to a hollow tool receivable in said chuck, a lubricant reservoir, and a single valve for effecting an initial flow of lubricant to said motor cylinder, and to said rotating mechanism, a flow of cleansing fluid to said cleansing means, thereafter a flow of pressure fluid to said feeding mechanism, and thereafter a flow of pressure fluid to said motor cylinder,

said events occurring in a predetermined sequence.

11. In a tool, a pressure fluid motor comprising a cylinder and a piston therein, a tool chuck, a chuck rotating mechanism, a fluid actuated feeding mechanism, a plurality of fluid conducting means for conducting air and water to a hollow tool receivable in said chuck, a lubricant reservoir, and a single valve for effecting an initial flow of lubricant to said motor cylinder and to said rotating mechanism, a flow of air to one of said cleansing fluid conducting means, thereafter a flow of pressure fluid to said feeding mechanism, and thereafter a flow of pressure fluid to said motor cylinder and a flow of liquid to said other cleansing fluid conducting means, said events occurring in a predetermined sequence.

12. In a tool, a pressure fluid motor comprising a cylinder and a piston therein, a tool chuck, a chuck rotating mechanism, and a fluid actuated feeding mechanism, a plurality of fluid conducting means for conducting air and water to a hollow tool receivable in said chuck, a lubricant reservoir, and a single valve for successively effecting an initial flow of lubricant to said motor cylinder and to said rotating mechanism, and a flow of air through said air tube, a flow of pressure fluid to said feeding mechanism, a flow of water to said cleansing fluid conducting means, and a flow of pressure fluid to said motor, said events occurring in a predetermined sequence.

13. In a tool, a pressure fluid motor comprising a cylinder and a piston therein, a tool chuck, a chuck rotating mechanism, a fluid actuated feeding mechanism, a plurality of fluid conducting means for conducting air and water to a hollow tool receivable in said chuck, a lubricant reservoir, and a single valve for successively effecting an initial flow of lubricant to said motor cylinder and to said rotating mechanism and a flow of air through said air tube, a flow of pressure fluid to said feeding mechanism, a flow of water to said cleansing fluid conducting means, and a flow of pressure fluid to said motor, said events occurring in a predetermined sequence, and automatic means responsive to pressure conditions within said motor for controlling a separate supply of lubricant from said reservoir to said motor cylinder.

14. In a tool, a pressure fluid motor comprising a cylinder and a piston therein, a tool chuck, a chuck rotating mechanism, a fluid actuated feeding mechanism, air and water tubes for conducting cleansing fluid to a hollow tool receivable in said chuck, a lubricant reservoir, a pressure chamber communicating with the motor distribution passages, a passage connecting said pressure chamber with said reservoir, a controlling valve hav-

ing an oil pocket therein, and passages connecting said pocket with said reservoir and with said rotating mechanism, said valve being adapted to effect an initial flow of lubricant to the motor, a flow of air to the air tube, a flow of pressure fluid to the feeding mechanism, a flow of water to the water tube, and a flow of pressure fluid to the motor, and means for supplying lubricant to the motor wholly independent of said first mentioned supply and only after the motor has started.

In testimony whereof I affix my signature.

CERTIFICATE OF CORRECTION.

Patent No. 1,771,675.

Granted July 29, 1930, to

GEORGE H. GILMAN.

It is hereby certified that error appears in the printed specification of the above numbered patent requiring correction as follows: Page 2, line 44, after the word "cylinder" insert the words "when pressure has been built up in said reservoir"; page 4, line 62, for "th" read the, and line 79, for the misspelled word "clinder" read cylinder; and that the said Letters Patent should be read with these corrections therein that the same may conform to the record of the case in the Patent Office.

Signed and sealed this 23rd day of September, A. D. 1930.

(Seal)

**M. J. Moore,
Acting Commissioner of Patents.**
